UNITED STATES PATENT OFFICE.

ARTHUR G. REMHILT, OF PHILADELPHIA, PENNSYLVANIA.

BINDER AND FASTENER.

1,056,452.

Specification of Letters Patent. Patented Mar. 18, 1913.

Application filed June 22, 1912. Serial No. 705,269.

To all whom it may concern:

Be it known that I, ARTHUR G. REMHILT, a citizen of the United States, residing at Philadelphia, in the county of Philadelphia and State of Pennsylvania, have invented certain new and useful Improvements in Binders and Fasteners, of which the following is a specification, reference being had to the accompanying drawings.

10 This invention comprehends certain new and useful improvements in temporary binders, and the invention has for its primary object a simple, durable and efficient construction of book and paper binder or 15 fastener, the parts of which can be cheaply manufactured out of sheet metal and the parts easily and quickly assembled and disconnected from each other. And the invention also aims to generally improve devices 20 of this class so as to render them more useful and commercially desirable.

With these and other objects in view, as will more fully appear as the description proceeds, the invention consists in certain 25 constructions, arrangements and combinations of the parts that I shall hereinafter fully describe and claim.

For a full understanding of the invention, reference is to be had to the following 30 description and accompanying drawing, in which,

Figure 1 is a longitudinal sectional view of one form or embodiment of my invention. Fig. 2 is a transverse sectional view thereof 35 on the line 2—2 of Fig. 1. Fig. 3 is a longitudinal section of another embodiment of the device. Fig. 4 is a transverse sectional view thereof on the line 4—4 of Fig. 3. Fig. 5 illustrates another embodiment hereinafter specifically described, and, Figs. 6 40 and 7 illustrate the two complementary parts of still another modification.

Corresponding and like parts are referred to in the following description and designated in the accompanying drawing by like reference characters.

In that embodiment of my invention illustrated in Fig. 1, the female member of my improved fastening device consists of a single strip of sheet metal doubled upon itself and shaped to form a cylindrical body portion 1 and a slightly larger preferably rounded head 2 at one end of the body portion, the body portion being tubular and 55 composed of two semi-cylindrical parts that

are separated from each other throughout their length by diametrically disposed longitudinal slots 3, said parts being integrally joined together at one end by the head 2, as clearly illustrated in the drawing. The 60 complementary member also consists preferably of a single or integral metallic strip doubled upon itself to form the disk-like head 4 and the locking members or arms 5 which possess resilient characteristics and 65 tend to spread apart, being formed at their relatively free extremities with outstanding and laterally projecting latch teeth 6 which are preferably of less width than the locking arms 5 and of a width substantially equal 70 to the longitudinal slots 3, although it is to be understood that the invention is not limited in this regard. These teeth are designed for locking engagement with keepers 75 which, in that embodiment of the invention now being described, are in the form of transversely elongated slots which are arranged in two longitudinally extending series on the two parts of the body portion 1, said slots terminating short of the side 80 edges of these two parts so as to leave smooth portions 8 which define or border upon the longitudinal slots 3.

From as much of the description as has preceded in connection with the correlated 85 views of the accompanying drawing, it will be understood that in the practical application of the device, after openings have been punched through the leaves or sheets to be temporarily or permanently bound together, 90 the female member of the fastener is preferably first inserted through the sheets, and the complementary member is then inserted into the first named member with the latch teeth 6 sliding along the smooth portions 8, 95 or, if desired, in the slots 3, whereby the male member will be properly guided until the required point has been reached, whereupon it may be turned axially so that the latch teeth 6 will snap out into the keeper 100 slots 7. In disengaging the device, it is only necessary to turn the male member of the fastener axially so as to disengage the teeth 6 from the slots 7, whereupon one part may be detached from the other. By making the 105 latch teeth 6 of a size to fit in the slots 3, it is evident that when the male member is turned axially to disengage the teeth from the keeper slots 7, said teeth will snap into the slots 3 and not only indicate that the de- 110

vice has been unfastened, but will insure the proper separation of the parts as the teeth will move along the slots.

It is to be understood that my invention is not limited to the exact construction, arrangement and proportions of the parts hereinbefore described, but that various changes may be made without departing from the scope of the invention, as defined 10 in the appended claim. For example, reference is to be had to the Fig. 3 wherein the female member designated 1^a differs from the corresponding part illustrated in Fig. 1, in that the member 1^a has its keepers in the 15 form of teeth 7^a punched through from the outside and the male member has its locking arms 5^a formed with longitudinal slots 6^a designed for engagement with the keeper teeth 7^a in an evident manner. If desired, 20 the male member of the device may be composed of two semi-cylindrical members 5^b formed with teeth 6^b punched through from the inside and designed for interlocking engagement with the teeth 7^a just described. 25 Where it is desired to fasten together only a few sheets, I may use complementary members like those illustrated in Figs. 6 and 7 wherein the male member designated 5^c is formed with teeth like the teeth 6 before described and the female member 1^c formed 30 with keeper slots 7^c, the two parts of the fastener differing from that embodiment of the invention first herein described, only in being made smaller, for a manifest reason, and

in that the female member has its relatively 35 free ends pointed, as indicated at 9, whereby it may be passed through sheets that have not been previously punched.

It will thus be seen that I have provided a very simple, durable and efficient construction of fastener of the character described, 40 and one that may be cheaply manufactured and readily assembled and disassembled and not liable to get out of order.

What I claim is:—

A fastener of the character described, consisting of telescoping members, one of which is formed of a single strip of metal doubled upon itself intermediate of its ends to form a head and the ends extended parallel to 50 each other and of semi-cylindrical shape, said ends being separated one from the other throughout their extent, and the other member being also formed of a single strip of metal doubled upon itself to form a head, 55 and inwardly yielding latch arms designed for insertion in between the two separated ends of the first named member which are formed with keepers, said arms being engageable with said keepers, substantially as 60 shown and described.

In testimony whereof I hereunto affix my signature in the presence of two witnesses.

ARTHUR G. REMHILT.
